US00D540919S

(12) **United States Design Patent** (10) Patent No.: **US D540,919 S**
(45) Date of Patent: **** Apr. 17, 2007**

(54) SHOWER FLANGE	D301,919 S	6/1989	Paul
(75) Inventor: Bryan Soriano , Baldwin Park, CA (US)	D302,202 S	7/1989	Paul
(73) Assignee: Newfrey LLC , Newark, DE (US)	D302,582 S	8/1989	Paul
(**) Term: 14 Years	D302,849 S	8/1989	Kohler, Jr. et al.
(21) Appl. No.: 29/230,588	D312,681 S	12/1990	Kohler, Jr. et al.
(22) Filed: May 24, 2005	D316,747 S	5/1991	Fleischmann
(51) LOC (8) Cl. 23-01	D318,099 S	7/1991	Reid et al.
(52) U.S. Cl. D23/249	D318,714 S	7/1991	Spangler
(58) Field of Classification Search ..... D23/238-257; D8/250-257, 300-322, DIG. 3, 350-353; 16/110.1; 4/675-678; 137/801	D318,717 S	7/1991	Spangler

CLAIM

The ornamental design for a shower flange, as shown and described.

DESCRIPTION

FIG. 1 is a front perspective view of the new design for a shower flange;

FIG. 2 is a top view of the new design for a shower flange, the bottom, right and left side views being mirror images; and,

FIG. 3 is a front view of the new design for a shower flange.
